Filed Aug. 15, 1969, Ser. No. 18,695

Term of patent 14 years

Int. Cl. D22—01

U.S. Cl. D22—1

FIG. 1 is a perspective view of a handgun grip showing my new design;

FIGS. 2 and 3 are opposite side elevational views thereof, the gun being shown in broken lines for illustrative purposes only;

FIG. 4 is a rear elevational view thereof;

FIG. 5 is a front perspective view thereof;

FIG. 6 is a view taken on line 6—6 of FIG. 2;

FIG. 7 is a view similar to FIG. 6 showing a second embodiment of my design.

The embodiment of the invention shown in FIG. 7 is in all respects similar to that of FIGS. 1 to 6 except for the hole therein being generally circular rather than generally square as in the embodiment of FIGS. 1 to 6.

The grip is fragmentarily shown in FIGS. 5, 6 and 7 for convenience of illustration.

I claim:

The ornamental design for a handgun grip, as shown and described.
